UNITED STATES PATENT OFFICE.

HENRY FORGER, OF CAMBRIDGE, OHIO, ASSIGNOR TO FRANK YESBERA,
OF TOLEDO, OHIO.

DESIGN FOR A SHADE FOR INCANDESCENT ELECTRIC LAMPS.

SPECIFICATION forming part of Design No. 37,418, dated April 25, 1905.

Application filed March 17, 1905. Serial No. 250,688. Term of patent 3½ years.

To all whom it may concern:

Be it known that I, HENRY FORGER, a citizen of the United States, and a resident of Cambridge, in the county of Guernsey and State of Ohio, have invented a certain new, original, and ornamental Design for a Shade for Incandescent Lamps, of which the following is a specification.

The accompanying drawing discloses an elevational view of the said shade.

I claim—
The ornamental design for a shade for incandescent electric lamps, as shown.

HENRY FORGER.
